(57) **CLAIM**

The ornamental design for a container carrier, as shown and described.

DESCRIPTION

FIG. 1 is a perspective view of a container carrier, showing our new design, shown in a folded configuration, with the prongs of a receiving aperture folded upward to accommodate a container, and further shown in a position of use with an exemplary container;

FIG. 2 is a front elevation view of FIG. 1 thereof, shown with the prongs of the receiving aperture in a flat configuration and further with the exemplary container removed;

FIG. 3 is a rear elevational view of FIG. 2;

FIG. 4 is a right-side elevational view of FIG. 2, the left-side elevational view being a mirror image thereof;

FIG. 5 is a top plan view of FIG. 2;

FIG. 6 is a bottom plan view of FIG. 2; and,

FIG. 7 is a top plan view thereof, illustrated in a flat configuration.

The broken lines are shown for the purpose of illustrating environmental subject matter of an exemplary container and form no part of the claimed design.
